UNITED STATES PATENT OFFICE

2,521,031

ATTENDANT'S STOOL

Weland D. Alspaugh, Warsaw, Ind.

Application May 9, 1949, Serial No. 92,179

5 Claims. (Cl. 155—81)

1

This invention relates to new and useful improvements and structural refinements in stools for barbers, dentists, beauticians, or other persons engaged in the performance of services upon a customer or patient seated in a chair, the principal object of the invention being to permit the operator or attendant to assume a sitting position while working, so that the comfort and efficiency of the attendant is not impaired by fatigue incident to working in a standing position.

One of the features of the invention resides in the provision of a unique base plate on which the attendant's stool is mounted, this base plate being adapted for positioning under the usual base of the customer's chair, whereby the attendant's stool is firmly and rigidly supported.

Another feature of the invention involves the provision of an adjustable leg member on the base plate for supporting the seat of the stool, by virtue of which leg member the position of the seat relative to the customer's chair may be adjusted in a horizontal as well as in a vertical plane.

Some of the advantages of the invention lie in its simplicity of construction, in its convenient operation, in its pleasing appearance, and in its adaptability to economical manufacture.

With the above more important objects and features in view and such other objects and features as may become apparent as this specification proceeds, the invention consists essentially of the arrangement and construction of parts as illustrated in the accompanying drawings, in which:

Figure 1 is a perspective view of the invention;

Figure 2 is a fragmentary cross sectional detail, taken substantially in the plane of the line 2—2 in Figure 1;

Figure 3 is a top plan view of the subject shown in Figure 1;

Figure 4 is a cross sectional view, taken substantially in the plane of the line 4—4 in Figure 3; and

Figure 5 is a cross sectional detail, taken substantially in the plane of the line 5—5 in Figure 1.

Like characters of reference are employed to designate like parts in the specification and throughout the several views.

Referring now to the accompanying drawings in detail, the invention consists of an attendant's stool designated generally by the reference character 10, such as may be conveniently and effectively employed in association with a customer's

chair, the usual circular base of the latter being illustrated by the phantom lines 12 in Figure 1.

The stool assembly 10 embodies in its construction a base plate 14 consisting of a crescent-shaped body portion 16 and an arcuate rim 18 which is secured at the ends thereof to the ends of the body portion 16 and coacts therewith to define a substantially circular opening 20, as illustrated in Figure 1.

10 The base plate 14 is intended to be positioned under the base 12 of the customer's chair in such manner that the base 12 covers the opening 20 while a portion of the base plate body 16 projects outwardly to one side of the base 12, this projecting portion having secured thereto an upright, substantially tubular socket 22. This socket may be welded or otherwise secured to the base plate portion 16 and if desired, suitable gusset plates 24 may be employed for additional reinforcement, as will be clearly apparent.

15 A substantially L-shaped leg member 26 has one arm thereof removably and rotatably positioned in the socket 22, and the remaining arm of the member 26 is provided with a second, upright tubular socket 28.

20 A second leg member 30 includes a lower portion 32 which is removably and rotatably positioned in the socket 28, while the upper end portion of the leg member 30, indicated at 34, is laterally offset with respect to the lower portion 32 and is formed with a helical groove 36.

25 A seat 38 is mounted, as will be hereinafter more fully described, on the upper end portion 34 of the leg member 30, and it will be apparent from the foregoing that the arrangement of the leg members 26, 30 is such that the position of the seat 38 relative to the customer's chair may be adjusted as desired in a horizontal plane, such as for example is indicated by the phantom lines 40, 42 in Figure 3.

30 In addition to the adjustability of the seat in a horizontal plane, means are also provided for adjusting the seat vertically, that is, for varying the distance of the seat from the floor, this means residing in the structure used for attaching the seat to the leg member 30. This is accomplished by providing a tubular adapter 44 on the underside of the seat 38, the adapter 44 being secured to the seat by means of suitable bolts 46 extending through a flange 48 with which the adapter is equipped, the adapter 44 being rotatably positioned on the upper end portion 34 of the leg member 30, as is clearly shown in Figures 4 and 5.

The adapter 44 is provided in the side wall thereof with an aperture 50 to receive a keeper element 52, preferably in the form of a sphere or ball, this element projecting from the aperture 50 into the groove 36 so that if the seat 38 together with the adapter 44 are rotated on the leg member 30, such motion will cause the seat to be lowered or raised as desired.

Means are provided for retaining the ball 52 in the aperture 50 and in engagement with the groove 36, said means involving the provision of a sleeve 54 which is positioned on the adapter 44 and is equipped with a set screw 56, the shank of the latter extending into the aperture 50 in engaging the ball 52, so that the set screw 56 actually performs a double function, namely, that of retaining the ball 52 in engagement with the groove 36, and secondly, for retaining the sleeve 54 in position on the adapter 44.

As has been already stated, the keeper element 52 is preferably ball-shaped, so that friction between the adapter 44 and the leg member 30 is substantially reduced.

It is believed that the advantages and use of the invention will be readily apparent from the foregoing disclosure and, accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

1. In combination with a customer's chair including a substantially circular base, an attendant's stool comprising a flat base plate positioned under the base of the customer's chair and projecting outwardly to one side thereof, an upright tubular socket secured to the projecting portion of said base plate, a leg member having a lower end portion removably and rotatably positioned in said socket, and a seat at the upper end of said leg member, wherein said base plate comprises a crescent-shaped body portion, and an areuate rim secured at the ends

thereof to the ends of said body portion and co-acting therewith to define a substantially circular opening, said socket being mounted on said body portion and said base covering said opening.

2. In combination with a customer's chair including a base, an attendant's stool comprising a flat base plate positioned under said base and projecting outwardly to one side thereof, an upright tubular socket mounted on the projecting portion of said base plate, an L-shaped leg member having one arm thereof removably and rotatably positioned in said socket, a second upright tubular socket provided on the remaining arm of said leg member, a second leg member having a bottom portion rotatable in said last-mentioned socket and a top portion laterally offset from said bottom portion, and a seat rotatably mounted on the top portion of said second leg member.

3. The device as defined in claim 2, together with means for vertically adjusting said seat on said second leg member.

4. The device as defined in claim 3, wherein the upper end portion of said second leg member is provided with a helical groove, said means comprising a tubular adapter provided on the underside of said seat and rotatable on the grooved portion of said second leg member, said adapter being formed with an aperture, and a keeper element positioned in said aperture and projecting into said groove, whereby said seat may be vertically adjusted by rotation thereof on the associated leg member.

5. The device as defined in claim 4, together with means for retaining said element in said aperture.

WAVELAND D. ALSPAUGH.
